UNITED STATES PATENT OFFICE

151,985

DESIGN FOR A FEED CARRIER

Simon A. Halls, Zumbrota, Minn.

Application August 13, 1947, Serial No. 140,847

Term of patent 14 years

(Cl. D14—3)

To all whom it may concern:

Be it known that I, Simon A. Halls, a citizen of the United States, residing at Zumbrota, in the county of Goodhue and State of Minnesota, have invented a new, original, and ornamental Design for a Feed Carrier, of which the following is a specification, reference being had to the accompanying drawing, forming part thereof.

Figure 1 is a side elevational view of a Feed Carrier, showing my new design.

Figure 2 is a top plan view thereof.

Figure 3 is a perspective view, with a portion broken away and shown in section, observing the front end thereof, and

Figure 4 is a perspective view observing the opposite end thereof.

I claim:

The ornamental design for a feed carrier, as shown.

SIMON A. HALLS.
